LIBRARY CARD TRAY

Arthur J. Pulos, Fayetteville, and Paul B. Sweeney, Jr.,
Syracuse, N.Y., assignors to Gaylord Bros., Inc., Syra-
cuse, N.Y., a corporation of New York

Filed Oct. 26, 1964, Ser. No. 82,310

Term of patent 14 years

(Cl. D74—9)

FIG. 1.

FIG. 2.

FIG. 3.

FIG. 4.

FIG. 5.

FIG. 1 is a view in end elevation of a library card tray embodying our new design and as seen from each end thereof;

FIG. 2 is a view of the card tray in side elevation as seen from each side thereof;

FIG. 3 is a bottom view of the card tray;

FIG. 4 is a perspective view of the card tray as seen from an observation point near one corner and slightly above the upper edge of the tray; and

FIG. 5 is another perspective view of the card tray, similar to the view in FIG. 4, but viewed from another angle.

We claim:
The ornamental design for a library card tray, substantially as shown.
